VEHICLE DIRECTION INDICATOR

William Edward Oshei, Brentford, England

Application March 22, 1935, Serial No. 12,481
In Great Britain March 26, 1934

7 Claims. (Cl. 177—329)

This invention relates to vehicle direction indicators of the type comprising a semaphore or like arm which may, for example, be pivotally mounted and swung upwardly to an indicating position.

In indicators of this type it is known to provide an electromagnet or solenoid which is adapted to be energised to swing the arm upwardly to its indicating position, the arm returning by gravity when the current is cut off. With such an arrangement, owing to the great difference in the leverage between the arms of the semaphore arm, it is found that the solenoid requires a considerable power to raise the arm which consequently causes a severe load on the battery.

It is also known to operate arms of this nature through medium of a suction cylinder which is connected to the suction of the engine, but a disadvantage arises in this form of device in that when proceeding around a corner an acceleration of the engine destroys the suction and the arm falls by gravity earlier than it is desirable.

It is an object of the present invention to provide an improved actuating device for semaphore signalling arms for vehicles by which the above disadvantages are eliminated.

The invention consists in means for operating vehicle direction indicators having a semaphore arm or the like comprising a power unit adapted to move the arm to a signalling position and means for reducing the power of said unit to a degree sufficient to maintain the arm in said position.

According to a feature of the invention the movement of the arm to the indicating position may be effected by suction-actuated means and independent means are provided adapted to retain the arm in the indicating position. The arm-retaining means may comprise an electromagnet or solenoid of relatively small power.

By such an arrangement it will be appreciated that when the arm is in the indicating position, in the event of the suction being destroyed the arm will still be retained in the indicating position until the current is cut off. Moreover, a solenoid of relatively small power is sufficient for the purpose of retaining the arm "up" when the initial resistance has been overcome.

According to a further feature positive means may be provided for returning the arm to its normal position. Thus a double acting piston may be provided in the suction cylinder, valve means being provided for alternately coupling either end of the cylinder to a source of suction.

Further features of invention will be herein-after described and defined in the claims.

In the accompanying drawing which illustrates the various forms of operating mechanism according to the invention:

Figure 1 is a side elevation partly in section of a suction-electric operating device.

Figures 2 and 3 are detail views of a suction control used in connection with the form shown in Figure 1.

In carrying the invention into effect according to one convenient mode, the semaphore arm 10 is adapted normally to hang in the vertical position and is pivotally mounted on a horizontal pin 11 supported by a pair of parallel arms connected to a suitable bracket or in any other suitable way. Arranged with its axis parallel with the semaphore arm and inwardly thereof is an actuator in the form of a suction cylinder 12 the piston 13 of which is provided with a rod 14 adapted to support a horizontally disposed actuator bar 15. This bar extends towards the semaphore arm above the pivotal axis thereof and is adapted to be lowered into operative relation with a cross pin 16 or abutment carried by the short lever of the semaphore arm, the arrangement being such that on downward movement of the piston the bar 15 moves downwardly into engagement with said cross pin or abutment 16 and causes a pivotal action of the semaphore arm, 15 raising the arm to the signalling position.

At a convenient position in the suction cylinder 12 a solenoid coil 17 or electromagnet is provided surrounding the piston rod and is connected to a battery lead 18. The other end of the coil 17 is earthed. The strength of the solenoid or magnet is such that when the arm is in the indicating position it will be retained in such position irrespective of the suction action by the attraction of the iron washer 14a on the piston rod. In the event of the suction being destroyed the arm will thus be maintained in its indicating position.

The semaphore arm is provided in the usual manner with a lamp so that it may be illuminated for night use and the lead 20 from the lamp is connected to a contact device 21 which may conveniently be coaxial with the cross pin or abutment 16 of the short lever of the arm. The arrangement is such that when the arm is moved to the indicating position the contact 21 will engage a spring contact 19 which is energised by the bridging of contacts 19a, 19b by the washer 14b when the arm is raised. The circuit for the lamp is completed by way of the vehicle frame.

The actuating bar 15 mounted upon the piston rod is provided with a light spring 22 which engages the cross pin 16 whereby when the arm is hanging vertically the bar rises off the cross pin and engages a part of the arm and thus prevents a swinging of the semaphore arm, the latter thereby being locked in its inoperative position.

In order to return the arm to the normal position, according to the present form, the piston 13 is double acting, a suction connection 23 being provided opening to the cylinder above the piston, 60

positive means is thus provided for returning the arm, avoiding the difficulty that sometimes occurs of the arm sticking in the signalling position or failing to return completely home when depending upon gravity for the purpose.

A suction control valve is provided adapted to be mounted in any convenient position.

This control device, see Figures 2 and 3, is provided with a pair of slide valves 24 and 25, one for the right hand signal and one for the left.

The valves are mounted upon a box 26 having a bore 27 connected to a source of suction 28.

The bore 27 has lateral branches 29 and 30 leading to ports 31 and 32 in the valve seat 33.

15 The box is also provided with ports 34 and 35 leading to connections 36 and 37 which are coupled up to the cylinder suction connections 23 and 33, respectively (Figure 1).

20 Similar connections 39 and 40 are provided for the other indicator.

With the valve in the position shown the port 35 is opening to atmosphere through the guide slot 41 while the port 34 is connected to suction through the recess 42 in the valve.

25 In operation, on the valve 24 being moved to the "operative" position (downwardly in Figure 2) the suction cylinder below the piston is coupled to the suction of the engine. At the same time a switch in the battery lead 18 is closed.

30 This switch may be actuated by being coupled to the valve 24.

The semaphore arm is thereby raised by the bar 15 engaging the abutment or pin 16 and when the arm is at the signalling position the solenoid 35 or electromagnet is energised by contact 24 engaging spring contact 19 and is effective to hold the arm raised in the event of the suction being destroyed. On moving the control valve 24 to its normal position the cylinder below the piston is 40 placed in communication with the atmosphere while above the piston communication is made with suction whereby the arm is positively lowered the solenoid at the same time being de-energised. When the arm reaches the signalling 45 position and the solenoid becomes effective to give the final movement and/or hold the arm extended, the cylinder may automatically be opened to atmosphere irrespective of the control device.

According to a modified arrangement of the 50 circuits for the coil 17 and lamp whereby a switch in the battery lead is unnecessary, the battery lead 18 may be coupled to the contact 19b while one end of the coil 17 is coupled to 19 and 19a, the other end being earthed. With such an ar- 55 rangement on 19a and 19b being bridged by 14b the coil 17 will be energized to attract 14a and the lamp will be illuminated by 21 engaging 19, the circuits being in parallel or again the battery lead may be connected to the coil 17, the coil 60 also being earthed, while the contact is insulated from the casing. In such case energization of the coil is effected when 21 engages 19, the coil and lamp being in series. With such an arrangement the contacts 19a and 19b are not required.

65 I claim:

1. Means for operating vehicle direction indicators having a semaphore arm comprising suction means for moving the arm to the signalling position, independent means normally inoperative but rendered operative by movement of the arm to the signalling position for retaining the arm in such position, and suction means operable to counteract said independent means and return the arm to its normal position.

2. Means for operating vehicle direction indicators having a semaphore arm comprising suction means for moving the arm to the signalling position, an electromagnet for retaining the arm in such position, means operative by movement of the arm to such position for rendering the electromagnet operative, and suction means for returning the arm to its normal position, and simultaneously rendering the electro-magnet inoperative.

3. In means for operating vehicle direction indicators having a semaphore arm, suction means comprising a cylinder having a double acting piston for moving the arm to and from the signalling position, means for connecting the cylinder to the intake manifold of the vehicle engine, and holding means acting by magnetic attraction on a part movable with the arm for retaining the arm in the signalling position.

4. A direction indicator for motor vehicles, comprising a signal device, an actuator for moving the same from one to the other of two positions, said actuator including a piston operatively connected to the signal device to actuate the same and a chamber in which the piston operates, a pair of fluid supply ports opening into the chamber at opposite sides of the piston for providing the required pressure differential on the piston to move it from and to an inoperative position, means for operatively applying and reversing the pressures acting on the piston, and electromagnetic means for magnetically retaining the piston in one of its positions in the event the pressure fails after moving the piston to such position.

5. A direction indicator for motor vehicles, comprising a signal device, an actuator for moving the same from one to the other of two positions, said actuator including a reciprocating member operatively connected to the signal device to actuate the same and means for moving the member in one direction, said moving means being hollow in order to guidingly receive the same during such movement, electromagnetic means arranged coaxially with said moving means for magnetically retaining the member in the position to which it is moved by said moving means, and an illuminating circuit for the signal device including separable switch contacts held closed by the electromagnetic means.

6. Means for operating vehicle direction indicators having a semaphore arm, comprising, in combination with said arm, means for moving the arm to a signalling position, an electromagnet for retaining the arm by attraction in such position, and means for applying to said first means a pressure of sufficient magnitude to overcome the attractive force of said magnet and return said arm to an inoperative position.

7. In combination with a source of fluctuating suction, such as the intake manifold of an internal combustion engine, an indicating device, suction means comprising a cylinder having a double acting piston for moving the device to and from an indicating position, and means for retaining the device in such indicating position with a force adapted to be overcome by a pre-determined suction influence from said source, whereby said suction means may return the device to an inoperative position against the holding force of said retaining means.
